UNITED STATES PATENT OFFICE

IRA C. BUCKMINSTER, OF BEVERLY, MASSACHUSETTS, ASSIGNOR TO UNITED SHOE MACHINERY CORPORATION, OF PATERSON, NEW JERSEY, A CORPORATION OF NEW JERSEY

COATING APPARATUS

Application filed May 19, 1924. Serial No. 714,493.

The present invention relates to apparatus for applying coatings to such surfaces as the foxing areas and bottoms of shoes and is illustrated as embodied in apparatus of the type disclosed in United States Letters Patent No. 1,476,047, granted December 4, 1923, on my application.

The machine disclosed in the above-mentioned Letters Patent includes a member movable, as by rotation, to apply a coating to the work and independently movable, as angularly and bodily, to vary the application by change in position of the work. Heretofore, this positioning movement has been produced wholly through effort on the part of the operator. This imposes a considerable burden, which it is the object of the present invention to reduce. I attain this end by effecting movement of the applying member through connections to power mechanism. The connections may be controlled by the operator, as by means of a treadle, and may produce both the angular and translational movements, either simultaneously or successively. Direct control of the member by the operator is also preferably provided for, an additional treadle being shown for this purpose.

In the apparatus set forth in the prior Letters Patent, a conical roll is employed, which may serve both as a gage and as an applying member, it having a solid body provided with a groove acting to convey along the roll the coating substance. To provide an applying member adapted for use in apparatus of the type referred to, in the operation of which the tendency to displace the coating substance to be applied will be minimized, I provide an applying member having a relatively small contact surface and comprising, as illustrated, a cone furnished by a helix, adapted to carry a body of the coating substance within it and at the same time perform the conveying function. In the use of such an applying member, the point of support of the helix is important, it being found that if the supporting member is carried entirely through the cone, so that its apex is closed, the travel of the coating substance along the applying surface is interfered with. I therefore arrange the helix to leave the apex

free from obstruction, preferably supporting it between its extremities.

When an applying member also serves as a gage, as in the case of the bottom-cementing roll of a foxing-cementer, it may be found convenient to vary the extent of application by the roll. This I accomplish by a shield removably mounted to cover a portion of the applying surface. When the base-portion, for example, of a conical member is thus shielded, the apex may be utilized in a foxing-cementer to increase the coating along the lower edge of the foxing-area, while the bottom of the shoe operated upon rests against the shield and receives no coating. Adjustment of the position of the conical member, with its shield, is also effected to determine the width of the band of cement to be applied.

A particular embodiment of the invention is illustrated in the accompanying drawings. Here,

Fig. 1 shows the improved coating apparatus in broken front elevation;

Fig. 2 is a side elevation thereof, with parts broken away;

Fig. 3 is a perspective view of the bottom-cementing roll and its more closely associated actuating and controlling elements;

Fig. 4 illustrates the connection for producing treadle-actuation of the carriage supporting the bottom-cementing roll;

Fig. 5 is an enlarged vertical, sectional detail on the line 5—5 of Fig. 1; and

Fig. 6 is a top plan view of the elements at the right of Fig. 3, parts being broken away.

The frame of the machine includes a column 10 provided with an overhanging arm 12 extending forwardly from the column. Journalled in this arm is a horizontal tubular shaft 14, at the forward extremity of which is mounted an applying roll 16. This roll has a frusto-conical applying surface, preferably provided by a circumferential series of helical springs 18 extending between heads at the extremities of a body-portion 20 (Fig. 5). Power may be furnished to rotate the shaft 14 from a motor 22 attached near the lower portion and at the rear of the col-

umn, and belted at 24 to drive a shaft 26 at a reduced speed. This shaft is journaled in the column and in a casing 28 enclosing the gearing, and is connected by reduction-gearing 30 to the shaft 14. The roll 16 is thereby continuously turned in one direction at a speed considerably less than that of the motor 22. As in the prior patent, the roll 16 is also oscillated at a greater speed than that of the movement of rotation just described, by lever mechanism 32 actuated by a cam-disk 34 fixed upon the frame. As a result of this, the rotation of the roll is alternately accelerated and retarded to more effectually rub the applied coating into the work, and to better distribute it at seams or other elevated or depressed portions.

Associated with the outer head of the roll 16 is a rotatable, yieldable feed and gage-wheel 36, the direction of rotation of which is opposite to that of the roll, so that while the work is being advanced by the engagement of the wheel, the periphery of the applying roll, moving in the reverse direction, produces an effect of brushing out the coating over the area acted upon. The wheel 36 is mounted upon a shaft 38 extending through the tubular shaft 14 and having a bearing 40 trunnioned upon the outer side of the casing 28, this permitting the feed-wheel to rise under the pressure of the work, so the latter may be brought into effective engagement with the applying roll. Rotation is imparted to the shaft 38 from the shaft 26 by reduction-gearing 42, 44, the intermediate elements of this being fixed upon the inner end of an idler shaft 46 journaled horizontally in the casing 28.

Below the roll 16 is a device which may both serve as a work-rest and as a means for applying cement to the bottoms of the shoes the foxing-areas of which are to be coated. This device includes a roll furnished by a conical helix 48 mounted upon a spindle 50 (Figs. 2 and 5). The spindle has, at its lower extremity, a flange 52 (Fig. 5), upon which the bottom of the helix rests, and at its upper extremity an enlargement 54 engaging the interior of a convolution of the helix between the ends of the helix. The spindle is journaled in and extends upwardly from the bottom of a receptacle 56, the inclined bottom wall 58 of which directs cement falling upon it to the lower convolutions of the helix. The manner of supply of the cement to the rolls 48 and 16 will be later described. Fixed upon the spindle 50, below the bottom of the receptacle, is a spiral gear 60 meshing with a like gear 62 upon a shaft 64 journaled in depending portions of the walls of the receptacle. This shaft is joined by spiral gearing 66 to a sectional shaft 68 extending horizontally from front to rear of the machine and having its parts splined together at 70 (Fig. 2), to permit the move-

ment of the receptacle, which will later be developed. The shaft 68 is coupled by a universal joint 72 to a short shaft 74 rotatable in the rear wall of the casing 28. Fast upon the shaft 74 is a pinion 76 driven through an idle pinion 78, which meshes with a gear 80 upon the shaft 46. As the roll 48 is rotated by the connections just outlined, cement flowing upon its lower convolutions from the bottom 58 of the receptacle 56 is elevated by the spiral, passing upward both between the convolutions and through the interior and overflowing at the apex, the excess not used upon the work returning to the receptacle. The opening at the last or upper convolution permits this conveying action without interference, the cement passing the enlargement 54 by traveling between the turns of the helix until it gains the open central portion above the head.

Variations in width of the foxing-area, or in the contour of this portion of the shoe operated upon, render it desirable to shift the roll 48 bodily along the roll 16, and also to change its angular relation thereto, turning it about its apex. To permit these changes to be made, the receptacle 56 is secured at the outer portion of a carrier 82, from the sides of which extend, rearwardly and upwardly, arms 84, 84 containing grooved arcuate guides 86, 86 (Fig. 3). Into the grooves extend pairs of projections 88, 88 fixed in forward extensions 90, 90 of a carriage 92 movable in ways 94 at the under side of the frame-arm 12. When the carrier 82 is oscillated by virtue of the travel of its guiding grooves over the projections 88, the angular position of the applying roll 48 is altered, the movement occurring substantially about the apex of the member as a center. Upon movement of the carriage 92 in its ways 94, a movement of translation is imparted to the roll 48, shifting its apex back and forth across the adjacent surface of the roll 16. The first movement so changes the relation of the work-engaging surface of the roll 48 in accordance with the contour of the portion of the shoe being operated upon, that contact may be had with a shoe-bottom along different portions without altering the effective action of the roll 16 upon the foxing-area. The bodily travel of the roll 48 along its companion varies the width of the band of cement laid upon such foxing-area. To produce these effects, the following power mechanism is provided.

Journaled in the carriage 92 is a transverse shaft 96, upon which are secured arms 98, 98 bearing at their forward ends gear-segments 100 meshing with corresponding segments 102 upon the portions 86 of the carrier. Loosely turning about the shaft 96 in a clockwise sense, as viewed in Fig. 3 is a sprocket-wheel 104 connected by a chain

106 to a sprocket-wheel 108 fast upon a shaft 110. The shaft 110 is mounted transversely, to rotate in the column 10, and is driven by bevel-gearing 111 (Fig. 2) from the shaft 26. The chain 106 may be kept taut in the travel of the carriage 92 by a roll 112 engaging its inner side, and carried upon an arm 114 turning loosely upon the shaft 110. A spring 116, extending between this arm and a casing 118, partially enclosing the sprocket-gearing, maintains the roll in yielding engagement with the chain. Arranged to turn about the shaft 96, and contacting frictionally at 120 with the outer face of the sprocket-wheel 104, is the cylindrical hub of a lever 122. Upon the outer extremity of the hub is a cam-face 124 co-operating with an opposite face 126 upon a sleeve 128 fixed upon the shaft. Relative rotation in a direction to separate these cam-faces is limited by contacting surfaces at 130 upon the cam members, these surfaces extending longitudinally of the shaft. Connected pivotally to the lever 122 is a block 132, through a vertical opening in which passes a rod 134 articulated at its lower extremity in one of the cups at the forked terminals (Fig. 2) of a lever 135 fulcrumed upon the base. A link 136 connects this lever to a treadle 137 movable upon the base. A collar 138 is secured upon the rod 134, and is movable thereby against the under side of the block 132 to turn the lever 122 in a clockwise direction, as viewed in Fig. 3 of the drawings. A spring 140 joins the lever 122 to a collar 142 secured near the lower portion of the rod 134, this spring acting to so turn the lever that its surface 124 is normally relieved from pressure against the companion cam-surface 126. Movement of the collar 142 to different points upon the rod permits the tension of the spring to be varied. Turning with the sprocket-wheel 104 is a clutch-disk 144 (Figs. 3 and 6) having a co-operating disk 146 fast upon the shaft 96 and driven from the associated disk when these elements are forced into engagement with an interposed friction member 148. A torsion-spring 150 (Fig. 3), surrounding the shaft 96, acts in a counter-clockwise direction, as viewed in Fig. 3, and exerts its force to hold the shaft, driven disk 146 and arms 98 in their normal positions, in which the roll 48 is located as illustrated in Figs. 2 and 3 of the drawings. When the operator depresses the treadle 137, the collar 138 is raised into contact with the block 132, and the lever 122 turned to force the cam-surface 124 against the opposite surface 126. The action of the cams is to shift the lever to the left (Fig. 3) along the shaft 96, so that its surface 120 bears frictionally upon the adjacent face of the sprocket-wheel 104, causing the latter to carry its disk 144 toward the disk 146. The friction material 148 thereupon communicates the clockwise rotation of the sprocket-wheel and disk 144 to the shaft 96, turning the arms 98 up, and, through the gear-segments, moving the carrier 82 over its guiding projections 88. As long as the operator continues to move the treadle down and thus revolve the cam-surface 124, this effect is maintained; but as soon as the treadle movement is stopped, rotation of the shaft carries the surface 126 away from the opposite surface 124, the engagement with which causes the pressure between the clutch-disks 144 and 146, and the rotation stops. If the operator removes his foot from the treadle, gravity or a spring, the latter not being shown in the drawing, carries the treadle and rod 134 to their normal positions, the shaft 96, with the elements secured thereto, and therefore the carrier 82, being returned to normal by the spring 150. It will consequently be seen that, by no greater effort than is necessary to overcome the weight of the treadle 137 and rod 134, the operator controls the action of the power mechanism to oscillate the carrier and change the angular position of the applying roll 48, this change being proportionate to the movement of the treadle.

Depending upon the character of the work, it may be necessary also to move the roll 48 inwardly along the roll 16, to increase the effective coating surface of the latter. The power mechanism may also be caused to accomplish this, either simultaneously with and throughout the just-described angular movement, or during a portion of such movement under the control of settable means 164, to be described. Mounted to turn upon the shaft 96 is a lever 154 (Fig. 3), upon the lower extremity of which is carried a gear-segment 156 meshing with a rack 158 fixed upon a portion of the frame. Upon the upper end of the lever 154 is a segment 160, in which is a series of openings 162. These are arranged with their centers along an arc for engagement by a spring-pressed pin 164 movable horizontally through an arm 166 mounted to turn about the shaft 96 between the lever 154 and the disk 146. At the inner side of this disk 146 is a projection 168 extending into the same vertical plane as the lever 166. If the pin 164 is placed in the first of the openings 162, or that toward the front of the machine, the arm 166 is substantially in normal contact with the projection 168. Consequently, when the movement of the disk 146 begins under the influence of the power mechanism made effective by depression of the treadle 137, engagement of the arm by the projection at once turns the lever 154 about the shaft. The lever is thereby caused to rock upon the rack 158 as a fulcrum, and the carriage 92 is slid toward the

rear of the machine in its ways 94, thus shifting the roll 48 inwardly, to increase the coating surface of the roll 16 presented to the work. With such an adjustment of the pin, the angular and bodily movements of the bottom gage and applying roll occur simultaneously. If the pin 164 is caused to enter an opening 162 toward the rear, as, for example, to the last of a series, contact between the projection 168 and the arm 166 may not occur during the angular movement of the roll 48. Consequently, there is no movement of translation imparted to it. For intermediate adjustments of the pin, the two movements may be differently combined, a certain amount of oscillation being imparted to the roll, followed by a combined movement of oscillation and translation.

The carriage 92 may be moved entirely by the effort of the operator to shift the roll 48 bodily, by a treadle 170 (Fig. 1) connected by a vertical rod 172 to a block 174 pivoted upon an arm 176. This arm is secured upon a sleeve 178 turning loosely about the shaft 110 (Figs. 3 and 4). The rod 172 is connected to raise the block 174 yieldably by a helical spring 180 surrounding the rod and supported upon a collar 182 fixed to it. A torsion-spring 184 encircles the shaft 110, and has one end hooked over the arm 176. This spring maintains the arm normally at its lowest limit of movement, this being variable by a screw 186 threaded through a depending portion of the arm and contacting with the frame. The adjustment obtained by the screw determines the normal position of the roll 48, and therefore the width of the roll 16 presented to the work. The sleeve 178 has upon it another arm 188, (Fig. 4) forked at 190 and engaging a horizontal pin 192 carried by lugs at the rear of the carriage 92. Upon depression of the treadle 170 by the operator, the rod 172 forces the spring 180 against the block 174 to rotate the sleeve 178, and, through the arm 188, slide the carriage in its ways to an extent determined by the amount the treadle is depressed.

The cement or other coating substance is contained in a tank 200 carried upon the upper surface of the arm 12 and having a discharge-opening controlled by a rotatable valve 202 (Fig. 2). As in the previous apparatus, there is delivery from this tank to both the upper portion of the roll 16 and to the roll 48, the coating substance in the latter instance dropping upon the bottom 58 of the receptacle 56. Here it is raised by the convolutions of the roll 16 along its outer surface to the upper extremity, for application to the bottom portion of a shoe held against the roll. The receptacle 56 is pivoted at 204 to the carrier 82, being held in the normal operating position by a spring-pressed pin 206 (Fig. 3) movable through

one of the arms 84 of the carrier. With the receptacle raised and locked in place by the pin, the roll 48 rotates in a vertical space 208 between the forward extremities of the carrier-arms. To allow the receptacle to be emptied, and to facilitate the removal of the roll for cleaning, the pin may be withdrawn from the registering opening in the receptacle, and this swung downwardly upon its pivot, tilting the roll forward through the opening 208 clear of the carrier-arms.

Sometimes manufacturers prefer not to coat the entire shoe-bottom at the time of cementing the foxing-area, but merely to apply a coating to the edge of the bottom adjacent to the foxing. To this end, a rigid work-supporting shield 210 (Fig. 3) is secured to the front of the carriage by screws 212 extending into the arms 84 through slots 214, these slots permitting the ready removal of the shield when the screws are loosened. The shield has side portions resting against the forward extremities of the arms, and a curved portion 215 generally conforming to the roll. This portion 215 acts as a fixed or non-rotatable gage-surface or work support which is interposed between the bottom coating roll 48 and the bottom of the shoe, and protects the inner portion of a shoe-bottom applied to it from the coating action of the roll. Under these conditions, only the edge of the shoe-bottom receives the application of cement, this being from the tip of the roll 48, which projects above the shield. Removal of the shield upon loosening the screws 212 exposes the work to the action of the entire length of the roll.

To govern the flow of cement to the rolls, the valve 202 has secured to it an arm 216 (Fig. 1), to which is pivoted, for ready separation, a rod 218. The lower end of the rod rests in the other depression or cup 220 at the forked end of the lever 135 beyond the link 136 connecting the lever to the treadle 137, which controls the power mechanism. Therefore, when this treadle 137 is lowered to apply power to change the position of the roll 48, the rod 218 is raised by the lever 135, opening the valve. This starting of the flow of cement may be caused to occur before the shifting of the roll, by the lost motion introduced by the spacing of the collar 138 from the block 132. To open the valve when the other treadle 170 is depressed, the rod 172 carries, adjustably fixed upon it, a contact member 222, which bears against a collar 224 secured to the rod 218 above the contact member. A tension-spring 226, connected to the base of the machine and to a collar 228 secured upon the rod 218, holds the valve normally closed. The tension of this spring may be altered by differently positioning the collar along the rod.

In using this machine, the operator sets the screw 186 (Fig. 2) to give a suitable initial

width of the roll 16 outside the roll 48 for the application to the foxing-area, and, if desirable, places the pin 164 in such a one of the openings 162 as will provide for an increase in this width under the influence of the power mechanism. The treadle 137, if the operator is to utilize the action of the power mechanism in positioning the roll 48 is depressed to an extent which will carry the roll initially to the desired point. A shoe 10 to be cemented is then pressed against the feed-wheel 36, as is illustrated in Fig. 5, this advancing the work against the rotating surface of the roll 16, and at the same time serving as a gage to produce a clean-cut line of demarcation between the coated and uncoated areas. The bottom of the shoe rests against the gage and applying roll 48, which, if only the edge adjacent to the foxing-area is to be 15 coated, has the shield 210 secured upon the ends of the carrier-arms 84. The lowering of the treadle 137 first raises the rod 218 to open the valve 202, permitting cement from the tank 200 to flow upon the roll 16 and into the receptacle 56, from which it is raised by the helix to the point of the applying roll 48. Continued downward movement of the treadle to the extent desired acts through the 20 rod 134 to clutch together, under the influence of the cam-surfaces 124 and 126, the driving and driven disks 144 and 146, respectively. By these, the shaft 96 is rotated to vary the angle of the roll 48, and at the same time, or as the angular movement progresses, the carriage 92 is shifted by contact of the projection 168 with the arm 166 (Figs. 3 and 25 6), to carry the roll 48 (and the shield 210, if it is used) across the roll 16 thereby to determine the width of the foxing-area to be 30 coated. When the movement of the treadle 137 stops, the driving action of the power mechanism is also discontinued by the separation of the cam-surface 124 from the surface 126. If the conditions surrounding the 35 work are such as to make only a bodily adjusting movement of the roll 48 desirable, (or the roll 48 and its shield 210) the operator uses the treadle 170, which reciprocates the carriage through the pin 192, the valve 40 202 being at the same time opened to initiate the flow of cement from the tank. 45

Having described my invention, what I claim as new and desire to secure by Letters Patent of the United States is:

50 1. In a coating apparatus, a member movable to apply a coating to work and independently movable to vary the applying action, power mechanism, connections to the power mechanism for producing each of such movements, and means for rendering one of said connections effective independently of the other.

55 2. In a coating apparatus, a member movable to apply a coating to the work and independently movable to vary the applying action,

ing action, power mechanism, connections to the power mechanism for producing each of such movements, and a movable controlling member for one of said connections arranged to produce movement of the applying member proportionate to its own movement.

3. In a coating apparatus, an applying member rotatable about an axis and variable in its angular relation to work in operative relation to it, power mechanism, and connections between the power mechanism and applying member constructed and arranged to move the applying member to vary the angular relation of the axis of the latter to the work at the point of contact of the applying member and the work and controllable by the operator independently of the rotation of the applying member.

4. In a coating apparatus, a rotatable applying member mounted to receive a movement of translation, power mechanism for rotating said applying member, and connections between the power mechanism and applying member arranged to effect bodily movement of the latter, said connections being controllable by the operator independently of the rotation of the member.

5. In a coating apparatus, a plurality of members rotatable about angularly related axes, each arranged for applying coating material, one of said members being mounted for translating movement relatively to the other independently of the rotation of said one of the members and in a direction parallel to the axis of rotation of said other member, and operator controlled power means for effecting such movement.

6. In a coating apparatus, a plurality of rotatable applying members, one of said members being movable relatively to the other in a plurality of directions independently of its rotation, and power means for effecting such relative movements.

7. In a coating apparatus, a rotatable applying member, and operator-controlled means for moving said member independently of its rotation, the member being mounted to move in another direction, said means being also arranged to cause the latter movement.

8. In a coating apparatus, a rotatable applying member mounted to receive a plurality of movements in addition to its rotation, means arranged to impart simultaneously to said member such plural movements, and settable means arranged to vary the extent of one of the movements.

9. In a coating apparatus, a rotatable applying member, means for imparting to said member a movement of translation in one direction independently of its rotation, the applying member being also mounted to move in another direction under the influence of said means, and movable means ar-

ranged to determine the time at which the influence of said means becomes effective.

10. In a coating apparatus, a movable applying member power mechanism, connections between the power mechanism and applying member, and a movable controlling member accessible for engagement by the operator and constructed and arranged to apply the power of said mechanism for imparting a movement of translation to the applying member, the extent of movement of the applying member being proportionate to that of the controlling member.

11. In a coating apparatus, a slidable support, a support tilttable upon that first named, a member for applying coating material journaled in the last-mentioned support, and rotatable power mechanism acting to impart sliding and tilting movements to the respective supports.

12. In a coating apparatus, a movable support, a support movable upon that first named, an applying member journaled in the last-mentioned support, power mechanism 25 acting to impart sliding and tilting movements to the respective supports, and operator-controlled means for the power mechanism arranged to govern the extent of such movements.

13. In a coating apparatus, a movable carriage, a carrier movable thereon, an applying member journaled in the carrier, and power mechanism for first moving the carrier and thereafter the carriage.

14. In a coating apparatus, a reciprocatory carriage, an oscillatory carrier mounted thereon, an applying member rotatable upon the carrier, a shaft journaled in the carriage, connections between the shaft and carrier 40 to oscillate the carrier, a power member rotatable about the shaft, and means for connecting the power member to the shaft.

15. In a coating apparatus, a reciprocatory carriage, an oscillatory carrier mounted thereon, an applying member rotatable upon the carrier, a shaft journaled in the carriage, connections between the shaft and carrier, a power member rotatable about the shaft, and co-operating cam members one of which 50 is secured to the shaft and another arranged for actuation by the operator and for contact with the power member.

16. In a coating apparatus, a frame, a reciprocatory carriage mounted thereon, an oscillatory carrier mounted upon the carriage, an applying member rotatable upon the carrier, a shaft journaled in the carriage, gearing connecting the shaft and carrier, co-operating gearing elements carried by the 60 shaft and frame, a power member rotatable about the shaft, and means for connecting the power member to the shaft.

17. In a coating apparatus, a frame, a reciprocatory carriage mounted thereon, an oscillatory carrier mounted upon the car-

riage, an applying member rotatable upon the carrier, a shaft journaled in the carriage, gearing connecting the shaft and carrier, co-operating gearing elements carried by the shaft and frame, a power member rotatable about the shaft, and means for connecting the power member to the shaft, said connecting means having a portion movable into co-operation with the gearing element of the shaft.

18. In a coating apparatus, a frame, a reciprocatory carriage mounted thereon, an oscillatory carrier mounted upon the carriage, an applying member rotatable upon the carrier, a shaft journaled in the carriage, 70 gearing connecting the shaft and carrier, co-operating gearing elements carried by the shaft and frame, a power member rotatable about the shaft, means for connecting the power member to the shaft, said connecting 75 means having a portion movable into co-operation with the gearing element of the shaft, and means arranged to vary the normal position of the movable portion of the gearing element upon the shaft.

19. In a coating apparatus, a frame, a reciprocatory carriage mounted thereon, an oscillatory carrier mounted upon the carriage, an applying member rotatable upon the carrier, a shaft journaled in the carriage, 95 a lever arranged to turn about the shaft, gearing connecting the lever and frame, a clutch member fast upon the shaft and having a portion for engagement with the lever, a driven clutch member normally loose upon the shaft, and operator-controlled cam mechanism arranged to effect engagement of the clutch members.

20. In a coating apparatus, a frame, a reciprocatory carriage mounted thereon, an oscillatory carrier mounted upon the carriage, an applying member rotatable upon the carrier, a shaft journaled in the carriage, a lever arranged to turn about the shaft, gearing connecting the lever and frame, a clutch member fast upon the shaft and having a portion for engagement with the lever, a driven clutch member normally loose upon the shaft, a cam member fixed upon the shaft, and a cam member movable by the operator 100 and co-operating with that first named and with the driven clutch member.

21. In a coating apparatus, a movable applying member, an operator-controlled device arranged to move the applying member, power mechanism connected to move the applying member in the same direction as the operator-controlled device, and operator-controlled means for governing the power mechanism in effecting this movement.

22. In a coating apparatus, a movable applying member, an operator-controlled device arranged to move the applying member, power mechanism connected to move the applying member in the same direction as the

operator-controlled device, operator-controlled means for governing the power mechanism in effecting this movement, a receptacle for a coating substance, means for controlling the flow of the coating substance to the applying member, and connections between said controlling means and each of the operator-controlled devices.

23. In a coating apparatus, a rotatable applying member movable independently of its rotation, a treadle connected to thus move the applying member, power mechanism, connections to the power mechanism for moving the applying member, and a treadle arranged to control the connections.

24. In a coating apparatus, a rotatable applying member movable independently of its rotation, a treadle connected to thus move the applying member, power mechanism, connections to the power mechanism for moving the applying member, a treadle arranged to control the connections, a tank for a coating substance, a valve for controlling the flow from the tank, and connections from both treadles to the valve.

25. In a coating apparatus, an applying member consisting of a conical helix.

26. In a coating apparatus, a receptacle for a coating substance, and a rotatable helical applying member having one extremity movable in such coating substance.

27. In a coating apparatus, a receptacle for a coating substance, and a rotatable, conical, helical applying member having its base-portion movable in such coating substance.

28. In a coating apparatus, an applying member consisting of a helix, and rotatable supporting means engaging such helix between its extremities.

29. In a coating apparatus, an applying member consisting of a rotatable helix arranged with the space between the convolutions at the apex free from obstruction.

30. In a coating apparatus, a frame, an applying member rotatable about an axis at the front of said frame, said member having a portion exposed for the application of work thereto, and a shield removably mounted to cover a portion of the axial extent of the exposed applying surface thereby to shorten it and arranged to serve as a rest for the work when applied to the exposed portion of the applying surface.

31. In a coating apparatus, a frame, a rotatable conical applying member journalled in said frame and having a portion exposed for the application of work thereto, and a shield interposed between said applying member and the work and removably mounted to cover the base-portion of the exposed work-contacting side of the conical applying member, thereby to limit the extent of the exposed surface.

32. In a machine for applying cement to the foxing area of shoes, a rotatable cement-

applying roll, a rest for the bottom of the shoe arranged adjacent to said roll and movable with respect thereto to regulate the relation of a shoe held against said rest with respect to said applying roll, and automatic means controlled by the operator to effect such regulating movement.

33. In a foxing-cementer for shoes, a foxing-cementing roll consisting of a circular series of helical springs, a bottom-cementing roll consisting of a conical helix, and means for rotating said rolls.

34. In a foxing-cementer for shoes, a foxing-cementing roll, a bottom-cementing roll consisting of a conical helix, and a shield arranged to cover the base-portion of said helix.

35. In a coating apparatus, an applying member made up of a supporting end piece and having a resilient peripheral applying surface comprising a coiled spring extending at an angle to said end piece, and an additional support for said spring disposed between its ends and within the periphery of the applying member.

36. In a coating apparatus, an applying member having a resilient conical periphery supported adjacent to the base of the cone, and means disposed within the periphery to support an intermediate portion thereof.

37. In a machine for applying cement to the foxing areas of shoes, applying mechanism constructed and arranged to coat both the foxing area and the bottom of a shoe and including a disk-like member the edge of which is adapted to bear against the upper of a shoe to define the edge of the foxing area to be coated, and a work support interposed between the bottom coating portion of the applying mechanism and the bottom of the shoe to cooperate with the bottom of the shoe and constructed and arranged to shield a portion of said applying mechanism.

38. In a machine for applying cement to the foxing areas of shoes, applying mechanism constructed and arranged to coat both the foxing area and the bottom of a shoe and including a disk-like member the edge of which is adapted to bear against the upper of a shoe to define the edge of the foxing area to be coated, a work support overlying part of the bottom-coating-part of the coating mechanism and arranged to engage the bottom of the shoe and constructed and arranged to shield a portion of said applying mechanism, and means for adjusting the position of said shielding work support with respect to said disk-like member to determine the width of the band of cement to be applied to the shoe.

39. In a machine for applying cement to the foxing areas of shoes, a rotatable cement-applying device a portion of which is frusto-conical in form, a rotary disk disposed adjacent to the frusto-conical portion of said

device and adapted to bear against the upper of the shoe to define the edge of the coated area, and a rigid non-rotatable work support engaging the bottom of the shoe and 5 mounted adjacent to the applying device.

In testimony whereof I have signed my name to this specification.

IR A C. BUCKMINSTER.
